DRESS

Mary M. Breeling, 4814 S. 22nd St., Omaha, Nebr.

Filed Feb. 26, 1959, Ser. No. 54,748

Term of patent 14 years

(Cl. D3—26)

The figure on the drawing is a front elevational view of a dress showing my new design, the back thereof being substantially similar in appearance. The lights and wires are mounted on an inner panel, an outer panel of sheer material being disposed over the outside of the light-holding panel.

I claim:

The ornamental design for a dress, as shown and described.
